UNITED STATES PATENT OFFICE.

JOSEPH H. ROACH, OF PHILADELPHIA, AND GOTTLIEB MILLER, OF NORRISTOWN, PENNSYLVANIA; SAID MILLER ASSIGNOR TO SAID ROACH.

UNDERFEED STOKER-FURNACE.

1,355,269.

Specification of Letters Patent. Patented Oct. 12, 1920.

Application filed April 16, 1918. Serial No. 228,948.

To all whom it may concern:

Be it known that we, JOSEPH H. ROACH, a citizen of the United States, residing at Philadelphia, Philadelphia county, and State

5 of Pennsylvania, and GOTTLIEB MILLER, a citizen of the United States, residing at Norristown, Montgomery county, and State of Pennsylvania, have invented and discovered certain new and useful Improvements in

10 Underfeed Stoker-Furnaces, of which the following is a specification.

Our said invention consists in various improvements in the construction and arrangements of parts of underfeed stokers, 15 whereby a more perfect feed is accomplished and the air regulated in zones to meet the requirements of combustion, and higher efficiency attained, all as will hereinafter be more fully described and claimed.

20 Referring to the accompanying drawings, which are made a part hereof, and on which similar reference characters indicate similar parts,

Figure 1 is a longitudinal section through 25 a furnace showing a stoking apparatus of our improved construction,

Fig. 2 a cross section through the same on line 2—2 of Fig. 1,

Fig. 3 a detail view partly in section and 30 partly in elevation of the left hand end of the structure shown in Fig. 1, and

Fig. 4 is a vertical transverse sectional view taken on line 4—4 of Figs. 1 and 3.

Fig. 5 is an inverted plan view as indicated by arrow 5 as shown at Figs. 1 and 3.

In said drawings, the portions marked A represent the walls of the furnace, B the supports for the grate bars and C the partitions dividing the space beneath the grate 40 bars and retort into separate chambers.

In the main the furnace structure shown is not widely different from other furnace structures of a more or less common type, and the description will therefore be confined chiefly to the details which constitute our improvements and the invention in the case.

The furnace is built with side ash pits 10, and a central air duct 11 extending under 45 the retort, as is usual. The vertical partitions C divide the space beneath the grate

bars and retort into side air chambers and a central air chamber, the side air chambers being beneath the main portion of the grate bars and dump plates 50 and the central air chamber beneath the retort and the head ends of said grate bars. Blast gates 12 are provided in the partitions C for regulating the blast of air from the main air duct 11 through the side air chambers, as shown. 55

The retort comprises sides 13, spaced an appropriate distance apart and held by distance ferrules 14 on cross tie-rods, or bolts 51, in a well known manner. Said retort has a sliding bottom 15, the outer end of 60 which has a shank 30 formed with a series of apertures 31 which project between ears 32 on a depending arm 33 of the ram 34 and is connected thereto by a pivot 35 extending through one of the perforations in said shank and perforations in said ears. The 65 ram 34 is connected to the piston rod 16 of the power cylinder 37 by which movement is imparted to the parts. Links 38 and 39 are also connected to a journal 52 70 on the depending arm 33 and in turn connected with the levers 40 and 41 pivoted at points 53 and 54 and having links 55 and 56 pivoted at their outer ends which connect with arms 57 and 58 on the journal ends 59 75 and 60 of the respective rock-shafts 21 thus providing for operating the movable grate-bars. Stationary twyer blocks 17 are secured on the top edges of said sides 13, and are formed with comparatively wide air 80 openings 18, as shown.

The grate-bars 20 are supported on the supports B, and part of them are mounted to move and part of them are stationary. In Fig. 2 the grate-bar on the right of the 90 figure is a stationary grate-bar, and the grate-bar on the left of the figure a movable or reciprocating grate-bar. Said movable grate-bars are operated in a usual manner by having their front lower edges recessed, 95 and with said recesses engaging ribs on the upper side of rock shafts 21, connected to the reciprocating parts, as above described and as shown. The stationary grate-bars are formed without recesses, but have curved 100 faces resting upon the ribs of the rock shafts, the faces being in the arc of a circle

so that said rock shafts may operate freely without affecting said grate-bars at all. Each of said grate-bars is formed with twyer openings to receive the blast of air 5 from the air chambers beneath. Said grate-bars may be arranged with the stationary bars and the movable bars in alternate relation, or in any other arrangement preferred. The alternate arrangement, will, of course, suggest itself as in the main appropriate, but we do not wish to limit our invention to any specific arrangement, as the purpose of the invention can be accomplished by arranging them in any relative 10 manner so long as part of them reciprocate, and part of them are stationary.

It is this feature of the construction which we regard as constituting the main part of the invention, inasmuch as it enables an operation to be carried out which is entirely 15 new.

We are aware that stationary twyer blocks are not new in stoking apparatus, and also that reciprocating grate-bars having the 20 twyer blocks formed on the inner or head ends thereof have heretofore been employed. In such construction the tendency is to squeeze the coal between the opposing grate-bars and force the fine coal into the twyers, 25 greatly restricting their openings and interfering with the passage of the air. For this reason, it has been necessary in such constructions to make the twyer openings very narrow to avoid carrying a large amount of 30 the fine coal and siftings into the lower passages beneath the stoker. With the construction as shown herein, wherein the twyer blocks are made stationary and the coal moved over the grate-bars by the movement 35 of part of said grate-bars only, the coal is fed past these twyer blocks and is distributed by the moving bars which operate with their head ends under the overhanging, or 40 projecting, tops of the twyer blocks. This 45 enables a definite motion to be given to the coal distribution from a retort of fixed width at the top as well as in its main part and makes it possible to have large air openings in the retort, thereby coking and thoroughly distilling the gases from the incoming 50 fuel.

The twyer blocks are fastened to the retort sides in any suitable manner, screw bolts 23 being shown as extending through flanges 55 at the top of the retort sides into the lower edge of the twyer blocks. By this means the twyer blocks are easily removed and replaced whenever necessary for any cause. The grate-bar is supported at its head end 60 by the main stoker frame instead of being supported by the top of the retort, as in the common construction of stoking apparatus. A further advantage of this construction is that the air distribution can be regulated to 65 meet the conditions of fire and nearly the

entire air blast can be directed into the retort and in a proper proportion under the grates without the use of partitioned grate-bars. It will be noted that the head end of the grate-bar is so constructed as to exclude air from the second or grate zone except by permitting its passage through the valves or blast-gates in the main frame as shown. Separate air zones are thus maintained, one from under the retort, between 70 its sides and the head ends of the grate-bars and the others under the grate-bars through the blast-gates.

Having thus fully described our said invention, what we claim as new, and desire 80 to secure by Letters Patent, is:

1. An underfeed furnace comprising a supporting structure, grate bars mounted on said supporting structure, some adapted to reciprocate while others remain stationary, 85 contacting ribs formed upon the stationary and reciprocatable bars, and a partition dividing the supporting structure into a plurality of air conduits and having a rocking section engaging the bars at the contacting 90 ribs adapted to actuate the reciprocatable bars and to slide in air retarding relation to the stationary bars.

2. An underfeed furnace comprising a supporting structure, grate bars mounted on said supporting structure, some adapted to reciprocate while others remain stationary, contacting ribs formed upon the stationary and reciprocatable bars, a partition dividing the supporting structure into a plurality of air conduits and having a rocking section engaging the bars at the contacting 95 ribs adapted to actuate the reciprocatable bars and to slide in air retarding relation to the stationary bars, and means 100 to drive said rocking section.

3. An underfeed furnace comprising a supporting structure, grate bars mounted on said supporting structure, some adapted to reciprocate while others remain stationary, 110 contacting ribs formed upon the stationary and reciprocatable bars, a partition dividing the supporting structure into a plurality of air conduits and having a rocking section engaging the bars at the contacting 115 ribs adapted to actuate the reciprocatable bars and to slide in air retarding relation to the stationary bars, means to drive said rocking section, and means to vary the arc of movement of the rocking section relative to the movement of the driving parts.

4. An underfeed furnace comprising a supporting structure, grate bars mounted on said supporting structure, some adapted to reciprocate while others remain stationary, 125 contacting ribs formed upon the stationary and reciprocatable bars, a partition dividing the supporting structure into a plurality of air conduits and having a rocking section engaging the bars at the con- 130

tacting ribs adapted to actuate the reciprocatable bars and to slide in air retarding relation to the stationary bars, means to drive said rocking section, and means to rock the 5 section twice to each cycle of movement of the driving parts.

In witness whereof we have hereunto set our hands and seals at Philadelphia, Penn-

sylvania, this 5th day of April, A. D., nineteen hundred and eighteen.

JOSEPH H. ROACH. [L.S.]
GOTTLIEB MILLER. [L.S.]
